VACUUM TUBE MOUNTING

Ross B. Hoffman, East Orange, N. J., assignor to
Federal Telephone and Radio Corporation,
Newark, N. J., a corporation of Delaware

Application February 6, 1943, Serial No. 474,977

14 Claims. (Cl. 250—27.5)

This invention relates to improvements in vacuum tube mountings, and is particularly directed to an arrangement for making a fluid-tight connection to and about the anode of a vacuum tube.

A general object of this invention is to provide an improved detachable coupling of general application.

Another object of this invention is to provide an improved detachable coupling which is especially adapted for use as a mounting for the anode of a vacuum tube.

A further object of this invention is to provide a detachable mounting for the anode of a vacuum tube, which at the same time serves to conduct a cooling fluid to and about the anode.

An additional object of this invention is to provide a detachable bayonet mounting for the anode of a vacuum tube, by means of which a socket is positively clamped to the anode while the bayonet connection serves to position the parts.

These and other objects of the invention will become apparent from the following description of a preferred form of mounting, taken together with a modification thereof, illustrated in the accompanying drawings in which:

Fig. 1 is a longitudinal view partly in section of a preferred form of mounting for the anode of a vacuum tube, in accordance with the present invention;

Fig. 2 is a transverse cross-sectional view taken along the line 2—2 of Fig. 1;

Fig. 3 is a longitudinal view through a modified type of mounting; and

Fig. 4 is a transverse section taken along the line 4—4 of Fig. 3.

As illustrated in the drawings, the anode of a vacuum tube, the remaining elements of which have not been illustrated, is shown at 10. This is adapted to be connected to an anode line in the form of a hollow metal cylinder 12. For the purposes of making this connection, the end face of the anode 10 has attached thereto the flange 14 of a compound ring 15. The other end of the ring is provided with a plurality of arcuate segments 16 shown in Fig. 2, for example, as being three in number. To the end of the anode line 12 is attached an externally threaded ring 18 which may be fastened to the end of the cylinder by means such as screws 20. The front end of the ring 18 is formed with an inwardly directed flange 22 which, together with the lateral face 23 of the ring 18 forms an internal annular

groove. The inwardly directed flange 22 of the ring 18 is provided with a plurality of arcuately shaped, circumferentially spaced openings 24 which permit entry of the arcuate segments 16 into the internal annular groove. It will be clear that when the segments 16 pass through the openings 24 and the anode is then rotated, the anode and the line 12 will be locked together except for the fact that in accordance with the present invention the width of the segments 16 are less than the width of the annular groove, so that there will be a longitudinal play between the two parts.

Screwed onto the ring 18 is an internally threaded ring 26 which has an inwardly directed flange 27 which fits into the space between the flange 14 of the compound ring 15 and the flange 22 on the ring 18.

The flange 22 forming one lateral face of the internal annular groove of the ring 18 has projecting longitudinally therefrom a plurality of stop pins 28 and 30, but pins 30 are of such length that they limit the rotation of the segments 16 within the annular groove, these pins extending substantially the width of this groove. The pins 28, however, are shorter, permitting rotation of the segments 16 so long as they are pressed against the lateral face 23 of the groove. If, now, the segments 16, attached to the anode 10, are inserted into the annular groove through the openings 24 and are rotated until they rest against the pins 30, the position indicated in Fig. 2, and the ring 26 is screwed outwardly on the ring 18, the flange 27 on the ring 26 pressing against the flange 14 on the ring 15 will move the anode 10 outwardly, and with it the segments 16, until the latter will be pressing against the opposite side of the annular groove. In this position the segments 16 will fall between the stops 28 and 30 and the two parts, the anode 10 and the line 12 will be rigidly locked together. Longitudinal movement between the parts is prevented by the action of the ring 26 having its flange 27 pressing against the flange 14, while relative rotation is prevented by the positioning of the segments 16 between the stops 28 and 30.

The invention is particularly adapted for use where the anode line 12 serves not only as an electrical conductor to the anode but also as a guide for a cooling fluid, such as air. This is particularly true if the anode is of the type illustrated, being provided at its end with a plurality of radial fins 32 positioned about a central core 34 with cooling channels 36 between the fins. If

the line 12 is provided with a suitable air inlet 50, it will be seen that this air moving within the line 12 will pass into the core 34 of the anode and outwardly through the cooling channels 36. The type of mounting described above, is sufficiently air-tight for this purpose.

One of the advantages of the above-described construction lies in the fact that a tight positive connection can be made without the use of separate contacts which have been proposed, for example, in prior art arrangements. The bayonets, in this case in the form of the arcuate segments 16, function solely to prevent relative rotation between the two parts, the tightness of the joint being brought about by the action of the ring 26, as described above.

The invention may be adapted for use in connection with water-cooled anodes, as is illustrated in Figs. 3 and 4. In this case the anode 110 extends partly within the anode line 112 which is again in the form of a hollow metal cylinder. The compound ring 115 is, in this case, attached about the anode instead of on the end thereof and its flange 114 extends radially outwardly beyond the periphery of the ring 118. The latter is attached to the end of the cylinder 112, similarly in the manner shown in Fig. 1, by means such as screws 120. The annular groove on the other end of the ring 118, is in this case formed by two spaced inwardly directed flanges 122 and 123, the flange 122 being formed with arcuate through openings 124 to permit entry of the segments 116 on the ring 115 into the internal annular groove. Due to the large diameter of the flange 114 on the ring 115, the internally threaded ring 126 on the externally threaded ring 118 does not need an inwardly directed flange but may press against the flange 114 either directly or preferably, through means such as a rubber gasket 136. The connection can be tightened and the parts locked in position in the same manner as the form of construction illustrated in Figs. 1 and 2. The flange 122 on the ring 118 is again provided with long stop pins 130 and short stop pins 128, between which the segments 116 are locked when the ring 126 presses against the flange 114 through the gasket 136 and presses these segments 116, against the flange 122. In accordance with a preferred arrangement, the anode line 112 is in this case, provided with a guiding vane 138 forming a water cooling channel 140 next to and about the anode 110, and a return channel 142, which may be adjacent the inner surface of the ring 118 and the cylinder 112. The rubber gasket 136, in this case, makes the joint water-tight.

While the mounting forming the basis of the present invention has been specifically described in connection with the attachment of the anode of a vacuum tube to its anode line which, at the same time, serves to direct a cooling medium to and about the anode, it is pointed out that the joint itself is not limited to the vacuum tube art, but is capable of use in other arrangements where a tight joint between two parts is desired, as will be appreciated by those skilled in this art. The joint is, however, specifically designed for the purposes described and permits a strong tight and rigid, but yet simple connection, a combination which was not obtainable by prior art arrangements. Accordingly, while I have described my invention and a particular modification thereof with some particularity in order that it may be clearly understood, it is pointed out that this description is made only by way of example and not as a limitation on the scope of my invention as set

forth in the objects and the accompanying claims.

I claim:

1. A mounting for vacuum tubes and the like comprising a metal cylinder, an externally threaded ring having means forming an internal annular groove at its outer end, attached to the end of the cylinder, said groove-forming means being provided with a plurality of arcuately shaped, circumferentially spaced openings connecting with said groove, a vacuum tube anode structure, a compound ring attached to said anode structure, said ring having an outwardly radially extending flange at one end and a plurality of arcuately shaped, circumferentially spaced, radially extending segments projecting from its other end and adapted to fit into said annular groove through said arcuate openings, whereby, when said anode structure is rotated, the arcuate segments will be out of alignment with said arcuate openings and the segments will be locked in the annular groove, the width of said segments being less than the width of the groove so as to permit longitudinal play of the segments in the groove, and an internally threaded ring screwed on said externally threaded ring and adapted to contact the flange on said compound ring, whereby, when said segments are in the groove and said internally threaded ring is screwed outwardly, the anode structure is moved away from the externally threaded ring by the action of the internally threaded ring on the radial flange of said compound ring and said segments are thus positioned and locked against a lateral face of the annular groove.
2. The combination according to claim 1, in which said compound ring is attached to the end face of the anode.
3. The combination according to claim 1, in which said compound ring is attached about the anode.
4. The combination according to claim 1, in which the said lateral face of the groove is provided with a first set of pins adapted to limit the rotation of said segments therein, and with a second set of pins of a shorter length than the first set of pins, permitting rotation of said segments in their unlocked position, but of sufficient length to prevent rotation of said segments after the latter have been rotated against the first set of pins and positioned against the lateral face of the groove by the action of said internally threaded ring.
5. The combination according to claim 1, in which said metal cylinder is hollow, and the end of said anode structure has a hollow core in communication with the hollow cylinder and is provided with a plurality of radially extending cooling passages opening into said hollow core.
6. The combination according to claim 1, in which said metal cylinder is hollow and in which said anode structure projects into the cylinder, in combination with means within said metal cylinder, forming passages for a cooling medium about the surface of the anode structure.
7. A mounting for vacuum tubes and the like comprising a hollow metal cylinder, an externally threaded ring attached at one end to an end of said cylinder, and having means at its other end forming an internal annular groove provided with a plurality of arcuately shaped, circumferentially spaced openings connecting with said groove, a vacuum tube anode structure, a compound ring attached to the end of said anode structure, said ring having an outwardly extending radial flange adjacent the

anode structure and a plurality of circumferentially spaced, radially extending arcuate segments projecting from its other end and adapted to fit into said annular groove through said arcuate openings, whereby, when said anode structure is rotated, the arcuate segments will be out of alignment with the arcuate openings and the arcuate segments will be locked in the annular groove, the width of said segments being less than the width of the groove so as to permit longitudinal play of the segments in the groove, and between the end of the externally threaded ring and the flange on said compound ring, and an internally threaded ring screwed on said externally threaded ring, said internally threaded ring having an inwardly directed flange positioned between the end of the externally threaded ring and the flange on said compound ring, whereby, when said segments are in said groove and said internal ring is screwed outwardly on said externally threaded ring, the anode structure is moved away from the externally threaded ring by the action of said inwardly directed flange against the radial flange of the compound ring, and said segments are thus positioned and locked against a lateral face of the annular groove.

8. The combination according to claim 7, in which the said lateral face of the groove is provided with a first set of pins adapted to limit the rotation of said segments therein, and with a second set of pins of a shorter length than the first set of pins, permitting rotation of said segments in their unlocked position, but of sufficient length to prevent rotation of said segments after the latter have been rotated against the first set of pins and positioned against the lateral face of the groove by the action of said internally threaded ring.

9. The combination according to claim 7, in which said anode structure has a hollow core in communication with the hollow cylinder, and is provided with a plurality of radially extending cooling passages opening into said hollow core, in combination with means for supplying a cooling fluid to within said hollow cylinder.

10. A mounting for vacuum tubes and the like, comprising a hollow metal cylinder, an externally threaded ring attached at one end to one end of said cylinder and having a pair of longitudinally spaced, inwardly directed flanges at its other end forming between them an internal annular groove, the outer of said flanges being provided with a plurality of arcuately shaped, circumferentially spaced openings connecting with said groove, a vacuum tube anode structure positioned within said hollow metal cylinder, a compound ring attached about said anode structure, said ring having a flange at one end extending outwardly beyond the periphery of said externally threaded ring, and a plurality of circumferentially spaced, radially extending arcuate segments projecting from its other end and adapted to fit into the annular groove through said arcuate openings, whereby, when said anode structure is rotated, the arcuate segments will be out of alignment with the arcuate openings and the arcuate segments will be locked in the annular groove, the width of said segments being less than the width of the groove so as to permit longitudinal play of the segments in the groove, an internally threaded ring screwed on said externally threaded ring, and a rubber gasket intermediate said internally threaded ring

and said outwardly extending flange, whereby, when said segments are in the groove and said internally threaded ring is screwed outwardly on said externally threaded ring, it pushes the anode structure through said gasket and outwardly extending flange, and said segments are thus positioned and locked against the outer inwardly directed flange forming a lateral face of the said groove.

11. The combination according to claim 10 in which the inwardly directed flange forming a lateral face of the groove is provided with a first set of pins adapted to limit the rotation of the segments therein, and with a second set of pins of a shorter length than the first set of pins, permitting rotation of said segments in their unlocked position, but of sufficient length to prevent rotation of said segments after the latter have been rotated against the first set of pins and positioned against the lateral face of the groove by the action of said internally threaded ring.

12. The combination according to claim 10, in combination with means within said hollow cylinder forming a cooling passage about the enclosed anode structure.

13. A detachable coupling for interconnecting two members, comprising an externally threaded ring having means forming an internal annular groove at its outer end, attached to the end of one of said members, said groove-forming means being provided with a plurality of arcuately shaped, circumferentially spaced openings connecting with the said groove, a compound ring attached to the other member, said ring having an outwardly radially extending flange at one end and a plurality of arcuately shaped, circumferentially spaced radially extending segments projecting from its other end and adapted to fit into the annular groove through the said arcuate openings, whereby, when said members are relatively rotated, the arcuate segments will be out of alignment with the said arcuate openings and the segments will be locked in the annular groove, the width of said segments being less than the width of the groove so as to permit longitudinal play of the segments in the groove, and an internally threaded ring screwed on said externally threaded ring and adapted to contact the flange on said compound ring, whereby when said segments are in the said groove and said internally threaded ring is screwed outwardly, the two members are moved away from one another by the action of the internally threaded ring on the radial flange of said compound ring, said movement being limited by the contacting of said segments against a lateral face of the said annular groove.

14. The combination according to claim 13, in which the said lateral face of the groove is provided with a first set of pins adapted to limit the rotation of said segments therein, and with a second set of pins of a shorter length than the first set of pins, permitting rotation of said segments in their unlocked position, but of sufficient length to prevent rotation of said segments after the latter have been rotated against the first set of pins and positioned against the lateral face of the groove by the action of said internally threaded ring.

ROSS B. HOFFMAN.
